UNITED STATES PATENT OFFICE.

JOHN KARHU, OF CALUMET, MICHIGAN.

AUTOMATIC DUMP-CAR.

962,356.

Specification of Letters Patent. Patented June 21, 1910.

Application filed February 5, 1909. Serial No. 476,317.

To all whom it may concern:

Be it known that I, JOHN KARHU, a citizen of the United States, residing at Calumet, in the county of Houghton, State of Michigan, have invented certain new and useful Improvements in Dumping-Cars; and I do hereby declare the following to be a full, clear, and exact description of the invention, such as will enable others skilled in the art to which it appertains to make and use the same.

This invention relates to cars and has special reference to a dumping car provided with side opening doors.

15 One object of the invention is to provide an improved construction of dumping car wherein the body of the car may have a flat floor, the body being arranged to tilt laterally so as to incline the floor.

20 Another object of the invention is to provide a car of this character with means whereby the edge of the body may be projected beyond the frame of the car a considerable distance when in dumping position so that the material contained in the car may be deposited beyond the ends of the ties of a railroad track on which said car is moving.

25 A third object of the invention is to provide a novel means of holding the car body level on the frame.

30 A fourth object of the invention is to provide a novel means of locking the doors of a car of this class, the means being either manually releasable for dumping the car when level, or automatically releasable for dumping the car when tilted.

35 A fifth object of the invention is to provide improved means for locking the releasing means against accidental release.

40 With the above and other objects in view the invention consists of a wheel supported frame whereon is mounted a car body or box adapted to be tilted to either side of the frame, together with improved locking means for the body and for lateral doors hinged thereto.

45 The invention further consists in certain novel details of construction and combinations of parts hereinafter fully described, illustrated in the accompanying drawings, and specifically set forth in the claims.

50 In the accompanying drawings, like characters of reference indicate like parts in the several views, and:—Figure 1 is a plan view of a car constructed in accordance with this

invention, the car body being shown in running position. Fig. 2 is a side elevation thereof. Fig. 3 is an end view thereof. Fig. 4 is a top plan view of one end of the car frame with the body removed. Fig. 5 represents a perspective and a face view of the improved form of hook used with this invention. Fig. 6 is a transverse section on the line 6--6 of Fig. 1, the view showing the car body in running or level position and disclosing the open position of one of the doors or sides in dotted lines. Fig. 7 is a similar view to Fig. 6 with the car body shown in dumping position. Fig. 8 represents a side elevation, an end view, and a plan view of certain brackets used to support the dumping rails. Fig. 9 is side and end views of the rollers or wheels used in connection with this invention. Fig. 10 is a detail perspective view of the locking device in position for releasing the car door from the body on one side. Fig. 11 is a perspective view similar to Fig. 10 but showing the parts in locked position. Fig. 12 is a perspective view showing a detail of one of the parts of the locking mechanism. Fig. 13 is a view of the door opening spring assembled. Fig. 14 is a view of the push bars shown in Fig. 13 disassembled. Fig. 15 is a view of the latch used with the locking mechanism illustrated in Figs. 10 and 11.

55 In the form of the device here shown the car is supported on spaced trucks 20 provided with the usual car wheels 21 arranged to run upon rails of the ordinary character. Carried on these trucks 20 is a car frame 22 and this car frame is provided with transverse members 23 whereon are carried filler blocks 24. These filler blocks are shorter than the members 23 and are positioned in the center of said members so that the ends of the filler blocks lie in spaced relation to the ends of the transverse members 23. In the angles formed between the filler blocks 24 and the members 23 are brackets 25 each of which is provided with a flange portion 26 arranged to rest on top of and each attached to the respective end of the filler blocks 24. These brackets are further provided with a portion 27 arranged to bear against the face of said end and a base 28 which rests on the transverse member or sill 23. Extending upward and inward at an acute angle to the base 28 the brackets are provided with a face member 29. Carried on these face members and secured thereto by

means of rivets or bolts 30 are rails which consist of anticlinally arranged portions 31, downwardly curved at their lower ends as indicated at 32, and the treads of these rails 5 are upwardly curved at the apex and unite to form a cusp 33. These rails are braced at their apex by means of a suitable bracing plate 34.

The frame of the car body proper includes 10 a pair of longitudinal side sills 35 which are united adjacent each end by spaced cross sills 36. Extending upward from the proximate or central cross sills 36 are posts 37. Supported on the inner faces of these posts 15 are car ends 38. These members 36 are so spaced that they embrace the rails 31, one of the members of each pair lying adjacent said rails toward the center of the car and the other member lying adjacent the rails 20 toward the end of the car. Supported in these members 36 are short shafts 39 whereon are rotatably mounted rollers or wheels 40 each of which is provided with a peripheral groove 41 so arranged as to form a flange 42 on each side of the wheel. These 25 wheels rest on the treads of the rails 31 and the diameters of the wheels at the bottom of the grooves 41 are equal to the diameters of the circles which form the sides of the cusps 33. Furthermore, the short shafts 39 are 30 spaced apart at such a distance that when one of the wheels 40 bears against one side of a cusp 33 the other wheel 40 will occupy the position shown in Fig. 7, that is to say, 35 at approximately the lower end of the rail 31 opposite the side of the cusp against which the first mentioned wheel bears.

Between the car ends 38 the car is provided with the ordinary car floor 43. Extending across the car immediately over the members 36 at each end of the car are transverse top members 44 and closing in the space between the members 36 are side members or car sides 45. These car sides do not 45 extend inward beyond the car ends 38 but terminate thereagainst. Carried in the members 44 at opposite ends thereof are pivot bolts 46 whereon are rotatably mounted hinge members 47 which are formed with 50 split portions extending over the car sides as indicated in Figs. 10 and 11 at 48. Secured to these split portions are side doors 49, the doors being thus hinged at the upper edge, and, if not secured, free to swing at the lower edge. These hinge members extend 55 downward at the inner ends and are provided with pivot pins 50. Between the inner ends of the hinge members extends a double compression spring member. This 60 member comprises a presser bar 51 having its outer end held by the pivot pin 50 and having its inner end forked as at 52. To the other pivot pin 50 at each end of the car is secured a presser bar 53 and this presser 65 bar lies between the sides of the fork 52.

Fixedly mounted on the presser bar 53 is a plate 54 and similarly mounted on the presser bar 51 is a plate 55. Between these plates is held a compression spring 56, and the presser bars are further provided with 70 stop members 57 which serve to limit the extension of said spring 56. The springs 56 are of sufficient strength so that, when the doors 49 are free to move, these springs will expand and raise the door to the position shown in dotted lines in Fig. 6, the 75 spring itself and the presser bars connected therewith assuming the position shown in Fig. 7. It is to be understood that but one side of the car is unlocked at a time so that but one side of the car is unlocked at a time so that 80 but one of the doors swings open, the amount of extension of the spring being merely enough to insure full opening of one door.

In order to retain the tilting body in its 85 level position suitable locking means are provided. Each of these locking means comprises a chain 58 preferably located at each corner of the car and each of these chains is preferably connected to the lower 90 end of one of the rails 31 as indicated at 59. Secured to the car body immediately above each of the chains 58 is a hook comprising a body portion 60 which is provided with a loop at its upper end for attachment 95 to an eye bolt 61 fixedly secured to the car body. This loop 60 consists of a single length of stiff wire or bar rebent upon itself and the lower ends diverge as at 62. From these diverging ends the extremities of the 100 bar are bent forward and around to form spaced eyes 63 wherein is held a pin 64. Upon the pin 64 is mounted a retaining hook comprising a single length of wire or bar 105 bent around the pin to form an eye 65 and provided with an inner upstanding terminal 66 and an outer upstanding terminal 67, the latter being substantially twice as long as the inner terminal. Slidable on the body of the hook 60 is a keeper ring 68 110 which is engageable over the end of the terminal 67 when the device is locked. The chain 58 terminates in a ring 69 adapted to receive the terminal 67 so that this ring is held between the two terminals 66 and 67, 115 and when locked, the ring 68 prevents the disengagement of the ring 69 from the terminal 67. When, however, the ring 68 is raised the terminal 67 is free to revolve and the revolution of this terminal carries with 120 it the terminal 66 and thus forces the ring 69 out of engagement with the hook 60. It will now be plain that if the hooks upon one side of the car be released the car may move freely toward the other side, the 125 amount of movement being limited by the wheels 40 on the released side engaging against the cusps 33.

In order to provide for holding the doors in locked position the sides 49 are equipped 130

with suitable braces 70 each of which has a lower end 71 which is bent inward beneath the sides of the car and terminates in an extremity 72 provided with ears 73 on the opposite sides thereof. The longitudinal members 35 of the car are provided with clips 74 each of which has a pair of spaced and perforated ears 75 adapted to receive a pivot pin 76. Extending under the members 35 are a series of latch members 77 having upturned portions 78 which engage the terminals 72 on the members 70 between the ears 73. These latch members 77 are secured to the pivot pins 76, being provided with perforated ears 79 for the purpose of receiving these pins. Furthermore, each of these latch members is provided with an inwardly extending portion or tail 80, for purposes hereinafter to be described. Springs 81 are provided, one for each of the latch members 77, and these springs normally hold the latch members in the position indicated in Fig. 15 so that the portion 78 of each member engages the portion 72 of its respective member 70.

In order to unlock the doors when the car body is in level position the longitudinal frame members 35 are each provided with a longitudinal groove 82 extending along the under side thereof and in each of these grooves is carried a cam bar 83 provided with a series of cams 84 corresponding in number and position to the latch members 77. The body of each of these cam bars lies wholly within the groove 82 wherein it moves, but the cams 84 project therefrom so that when one of these cam bars is drawn toward the proper end of the car the latch members 77 on the side of the car which the cam bar in question controls, are engaged by the cams 84 and the portions 78 of these latches are forced downward and disengage from the portions 72 of the members 70. In order to provide for this movement of the cam bar levers 85 are pivoted on pins 86 secured in the members 35, there being one of these levers on each side of the car. Adjacent these levers the ends of the cam bars are downwardly bent as at 87 and the downwardly bent ends are each connected to their respective levers 85 by means of links 88. By this construction when the lever 85 is pulled toward the end of the car the cams 84 are brought into operation and the latches released as previously described.

In order to provide for the automatic release of these latches when the car is dumped to one side or the other there is mounted on the car frame beneath each of the members 70 and in the path of the tail 80 a small roller 89 which is so arranged that as the car body swings to the position indicated in Fig. 7 the tail 80 of each of the latches will strike against its respective roller 89 and trip the respective latch.

In order to prevent accidental unlocking of the car sides a supplementary lock is provided. In this lock each of the members 70 is provided with a suitable perforation 90 to receive a bar 91 having an angularly disposed end 92. Pivotally mounted in alignment with the end 92 of each bar 91 is a cam member comprising a base 93 provided with an offset handle 94 and having an outwardly extending portion 95 provided with a cam slot 96. The base 93 is further provided with an arcuate slot 97 concentric with the pivot 98 of this member, and a set or lock screw 99 extends through the slot 97. Fixedly mounted on each of the bars 91 is a series of locking loops 100 provided with inwardly bent ends 101 and each of these ends is arranged to engage over an outwardly extending terminal 102 projecting from the portion 78 of each latch 77. In the operation of this portion of the device the parts will be seen in unlocked position in Fig. 10 and in locked position in Fig. 11. In the first mentioned figure it will be noted that the end 92 lies at the outer extremity of the cam slot 96. Now, when the handle 94 is depressed the broad end 92 will be forced to follow the path of the cam slot 96 and the rod 91 will consequently be rotated in such direction as to move the lower ends 101 of the members 100 inward so that these lower ends will engage beneath the ends 102 of the respective latches 77, thus preventing the disengagement of these latches from the terminals 72 of the respective member 70 so long as the cam member shall have its handle 94 depressed. This position of the cam member may be assured by turning the lock nut 99 so that movement of the cam member is prevented.

In the general operation of the device when it is desired to dump the car, whether automatically or manually, the set screw 99 is released and the handle 94 moved upward so that the latch release mechanism is free to operate. If it be desired to dump the car in level position the handle 85 on the proper side is then moved toward the end of the car and the door will be released in the manner previously described. If it be desired to tip the car and simultaneously dump the same the hooks 60 on the opposite side from which it is intended to dump the car are released and a slight start given the car in the direction of dump. This causes the car to assume the position shown in Fig. 7 and as the car takes this position the latches 77 on the lower side are released by reason of the tails 80 striking the rollers 89.

There has thus been provided a simple and efficient device of the kind described and for the purpose specified.

It is obvious that minor changes may be made in the form and construction of this invention without departing from the mate-

rial principles thereof. It is not therefore desired to confine the invention to the exact form herein shown and described, but it is wished to include all such as properly come within the scope of the appended claims.

Having thus described the invention, what is claimed as new, is:—

1. In a dump car of the class described, a car frame, pairs of antieclinally arranged tracks supported transverse said frame adjacent each end thereof, a car body, wheels rolling on said tracks and supporting said car body, the apex of each pair of tracks having the outer face thereof curved upward 15 in circular arcs to form a cusp, said arcs being arcs of circles of equal diameter to the rolling surface of said wheels.
2. In a dump car of the class described, a car frame, pairs of antieclinally arranged tracks supported transverse said frame adjacent each end thereof, a car body, wheels rolling on said tracks and supporting said car body, the apex of each pair of tracks having the outer face thereof curved upward 25 ward in circular arcs to form a cusp, said arcs being arcs of circles of equal diameter to the rolling surface of said wheels, and coacting locking elements on said frame and body to hold the body from movement relative to the frame.
3. In a dump car of the class described, a car frame, a car body tilttable transversely of said frame, side doors for said body, hinges at the upper edges of said side doors 35 to connect the doors to said body, downwardly projecting inner ends formed on said hinges, presser bars connected to said hinge ends, collars on said bars, a compression spring held between said collars, and releasable locking elements on said doors and body to hold the doors closed against the action of said spring.
4. In a dump car of the class described, a car body, a door hinged to the side of said body, a latch pivoted to the car body, a member on said door engageable by said latch, a spring normally holding said latch engaged with said member, a bar slidably mounted beneath said latch on said body, a cam on said bar engageable with said latch to release the same from said member, and a lever to move said bar.
5. In a dump car of the class described, a car body, a door hinged to the side of said body, a latch pivoted to the car body, a member on said door engageable by said latch, a spring normally holding said latch engaged with said member, a bar slidably mounted beneath said latch on said body, a cam on said bar engageable with said latch to release the same from said member, a lever to move said bar, and releasable means to prevent the release of said latch.
6. In a dump car of the class described, a car body, a door hinged to the side of said body, a latch pivoted to the car body, a member on said door engageable by said latch, a spring normally holding said latch engaged with said member, a bar slidably mounted beneath said latch on said body, a cam on said bar engageable with said latch to release the same from said member, a lever to move said bar, an outwardly extending terminal formed on the latch, a rotatable shaft mounted on said door, a keeper 70 fixed on said shaft and engageable over said terminal, an arm on said shaft, means to move said arm, and other means to lock the first mentioned means.
7. In a dump car of the class described, a car body, a door hinged to the side of said body, a latch pivoted to the car body, a member on said door engageable by said latch, a spring normally holding said latch engaged with said member, a bar slidably 80 mounted beneath said latch on said body, a cam on said bar engageable with said latch to release the same from said member, a lever to move said bar, an outwardly extending terminal formed on the latch, a rotatable shaft mounted on said door, a keeper fixed on said shaft and engageable over said terminal, an arm on said shaft, a cam plate pivotally mounted on said door and provided with a cam slot engaging over said 85 arm, a handle formed on said cam plate, said cam plate being further provided with an arcuate slot concentric with the pivot of the plate, and a locking screw passing through said arcuate slot and arranged to 90 frictionally engage said plate and prevent the movement thereof.

JOHN KARHU.
